UNITED STATES PATENT OFFICE.

WILLIAM ACHESON, OF SUPERIOR, NEBRASKA.

CONCRETE-MIXING MACHINE.

1,211,270.

Specification of Letters Patent. Patented Jan. 2, 1917.

Application filed February 8, 1916. Serial No. 77,068.

To all whom it may concern:

Be it known that I, WILLIAM ACHESON, a citizen of the United States, residing at Superior, in the county of Nuckolls and State 5 of Nebraska, have invented new and useful Improvements in Concrete-Mixing Machines, of which the following is a specification.

The invention relates to a mixing machine, and more particularly to the class of concrete or cement mixers.

The primary object of the invention is the provision of a mixing machine of this character wherein the cylinder or drum thereof is mounted in a novel manner for rotation 15 and tilting movement so that it can be readily dumped after the contents has been thoroughly mixed in the rotation of the same.

Another object of the invention is the provision of a mixing machine of this character wherein the same in its entirety is novel in construction to assure the thorough mixing 20 of the materials therein with despatch.

A further object of the invention is the provision of a mixing machine of this character wherein the cylinder or the drum there- 25 of is mounted in a manner to permit the adjustment of the same for the convenient filling of the cylinder or drum.

A further object of the invention is the provision of a mixing machine of this character which is simple in construction, thoroughly reliable and efficient in its operation, strong, durable and inexpensive in 30 manufacture.

Other objects will be in part obvious and in part hereinafter pointed out.

The invention accordingly consists in the features of construction, combination of elements and arrangement of parts hereinafter exemplified in the construction described, and the scope of the application of which will be indicated in the appended claim.

In the accompanying drawings: Figure 1 45 is a side elevation of a mixing machine constructed in accordance with the invention; Fig. 2 is a front elevation.

Similar reference characters indicate corresponding parts throughout the several 50 views of the drawings.

Referring to the drawings in detail, the mixing machine comprises a bed or base frame A, from the side sills 10 of which rise vertical uprights 11, to the upper ends of 55 which are fixed rearwardly inclined braces 12, the same being also fixed to the side sills

10 of the bed or base frame A. Between the uprights 11 is arranged a locking frame B including the side beams 13 and a rear cross beam 14, the beams 13 being swingingly supported upon pivots 15 which are journaled in the uprights 11 near the upper ends thereof to permit the rocking of the frame B when the occasion requires.

Secured to the side beams 13 of the rock- 60 ing frame B near the front end thereof are top and bottom hoop sections 16 and 17, respectively, which encircle a rotary cylinder or drum 18 having mounted exteriorly thereon a circular track 19 engaging rollers 20 70 which are journaled in the bottom hoop section 17 to minimize friction and permit the free rotation of the cylinder or drum, which is driven in a manner presently described. The cylinder or drum 18 at its rear closed 75 end has thereon spaced cross strap iron 21 to which is bolted or otherwise fixed a gear 22, which may be formed with a central stud shaft journaled in a suitable bearing secured to the cross beam 14 of the rocking frame B, 80 and meshing with this gear 22 is a pinion 25 secured to a driven shaft 26 journaled in suitable bearings carried upon the cross beam 14 of the said rocking frame B, and this driven shaft at its outer end carries a 85 sprocket wheel 28 over which is trained an endless sprocket chain 29, the same being also trained over a sprocket gear 30 secured to the counter-shaft 31 journaled in one up- 90 right 11 and a bracket 32 mounted thereon, the shaft 31 being also fitted with a belt 95 wheel 33 adapted to be driven in a manner presently described.

Mounted upon the base or bed frame A is a suitable motor 34 over which is adapted to be trained an endless belt 35 which is also trained over the belt wheel 33 so that on the starting of the motor 34 the cylinder or drum 18 will be rotated thereby.

Mounted interiorly of the cylinder or 100 drum 18 contiguous to the inner side face thereof at intervals are beveled wings or blades 37, each being formed with a curved outer end which terminates spaced from the front open end of the said drum or cylinder, 105 and these blades or wings act upon the contents of the cylinder or drum for the thorough mixing thereof on the rotation of the same, the materials being introduced into the cylinder or drum through the open end 110 thereof, and when these materials are introduced the said cylinder or drum is disposed

in a vertical position. After the thorough mixing of the material the cylinder or drum 18 is tilted at a forward inclination, which permits the dumping of the mixture therefrom.

Secured to the cross beam 14 of the rocking frame A is a prop 39 to which is fixed a handle 40, the same being also fixed to the top hoop section 16, and this handle is of the required length to project a distance beyond the open end of the cylinder or drum 18 so that the rocking frame B can be swung for the adjustment thereof.

The machine is constructed in such a way that the drum or cylinder will revolve at any angle, that is, the said drum or cylinder will revolve when the machine is in position for filling or when being dumped or at any other angle or position desired. On account of the particular construction of the machine the cylinder or drum has an open end constituting an unobstructed mouth or feeding end, thus allowing more ease in feeding or filling and also permitting inspection and observation of the condition of the mixture when it is being mixed so as to observe when the mixture is ready to be dumped, and when the machine is being emptied the cylinder or drum and its contents can be more readily viewed to determine whether a wheelbarrow or other conveyer will hold the entire contents of the cylinder or drum.

The machine, by reason of its particular construction, is more nearly at a balance and less strength and force is, therefore, needed to dump the cylinder or drum, that is, when the machine is in dumping position the lever for dumping may be operated by one hand. It will be apparent that by reason of

the construction of the machine and the parts thereof which bear such relative position with respect to each other and the machine bears such relative position to the sand and cement being fed into it that the act or operation of filling the machine and the act 45 or operation of watching the mixture, as before stated, and the act or operation of dumping the machine, can be effected by the operator while standing in one place or position, thus saving time and labor and allowing more cement to be mixed in the machine in the same length of time than if the operator had to change his position or go to the other side of the machine to dump the cylinder or drum thereof. 50 55

Having thus described my invention, I claim:

In combination, a pair of spaced standards, a bar connecting the standards, a tilting frame journaled between the standards 60 adjacent one of its ends, extensions formed on the frame and normally engageable with said bar, a mixing drum rotatively mounted within the frame, hoop sections carried by the frame and encircling said drum, a 65 bracket secured to one end of the frame and upstanding therefrom, a handle having one end secured to the bracket and intermediate portion being secured to one of the hoop sections, and means carried by the standards 70 and frame for rotating said drum.

In testimony whereof I affix my signature in presence of two witnesses.

WILLIAM ACHESON.
